LAUNDRY IRONING AND PRESSING
MACHINEAugust Dahler, Bronx, N. Y., assignor of one-half
to Philip Band, New York, N. Y.

Application July 27, 1937, Serial No. 155,855

14 Claims. (Cl. 223—57)

This invention relates to new and useful Improvements in laundry machines, and more particularly to machines for pressing and ironing, and it has for its object to provide a machine capable of ironing a shirt in one single operation.

Aside from the above accomplishment, another advantage of my device resides in the fact that the said machine may be operated by only one person, thus effecting a great saving in machinery and the incidental cost of same, as the attainment of the above result, that is the ironing of a shirt, has hitherto required the employment of three to four different machines, with the corresponding number of operators to attend to these.

This invention may thus be said to reduce very considerably the array of machines, hitherto necessary in laundry work, with an incidental saving of space occupied by said machinery; at the same time a saving of labor is affected, as hereinbefore stated, thus bringing about as a total an immense saving obtained by the use of my devised machine, hereinafter described.

The present invention embodies further new and useful features, in addition to those of my invention for which the U. S. Patent No. 2,086,900, has been granted to me.

As the construction of my invention is comparatively simple, the cost of manufacturing the same should be proportionately low.

With the above and other objects in view, this invention consists of the novel features of construction, combination, and arrangement of parts, hereinafter fully described, claimed and illustrated in the accompanying drawings forming part of this specification, and in which similar characters of reference indicate corresponding parts in all views, and in which:—

Figure 1 is a side elevational view of my device, in open position, that is with the lid or upper part of said device swung open.

Figure 2 is an end elevational view of said device.

Figure 3 is a top plan view of the device.

Figure 4 is a transverse sectional view, taken on the line 4—4 in Figure 3;

Fig. 4a is a fragmentary view, similar to that of Fig. 4, showing the device in open position;

Figure 5 is a detail sectional view of my device, taken on the line 5—5 in Figure 3; and

Fig. 6 is a sectional view, taken on the line 6—6 of Fig. 3.

Referring more particularly to the drawings, my device may be said to consist of three major

parts, namely, a lid, or upper part 10, a center part 11, and a bottom part 12.

The center part 11 is fixedly secured at one end thereof to a standard 13, by means of a hollow shank 14, while the other end of said center part is made with a reduced portion 15, as may be seen in Figure 5, adapted to accommodate an adjustable cone-shaped member 16, which latter has for its purpose to receive thereon the collar of a shirt during the ironing operation of said 10 shirt.

The center part 11 has its sides formed with somewhat rounded portions 17, as shown in Figure 1, in order properly to fit the form of a shirt.

In said center part, the bottom 18 thereof extends forward of the reduced portion 15, as shown in Figure 5; said extended bottom portion serves as a support for the cone-shaped member 16; while the said center part proper is formed with a cylindrical opening 19 therein, as shown in Figure 5, to permit of the arrangement of suitable operating means therein, in the present instance a rod 20. It will be noted that said rod 20 is extending through the shank 14, and through the standard 13 one end thereof, terminating in manipulating means, for instance, as shown a wheel 21, arranged upon the outside of said standard. The other end of said rod 20 terminates into a right-angle bent portion, which may be seen in section at 60 in Figure 5. Said bent portion, which is located under the cone-shaped member 16, will actuate the latter when manipulated, as mentioned by means of the wheel 21, and cause it to fit the collar of the shirt to be ironed; said cone-shaped member 16 is adjusted to the size of a collar, as it is adapted to slide vertically upon the studs 22 arranged upon the extended bottom portion 18 of the center part 11, as may be seen in Figure 1. The end of the bent rod 20 may also be seen in Fig. 6.

In actual operation the body of a shirt 52 is placed upon the center part 11, and the collar 54 is accommodated by the cone-shaped member 16, while in this operation a spring 23, secured to said cone-shaped member 16, is adapted to hold the collar in position, by pressing on to the latter.

The bottom part 12, which may be operated in any suitable manner, for instance, by a lever 24, as shown in Figure 1, is formed with a somewhat concave upper surface adapted to snugly fit the lower body portion of the center part 11, and thus contributing to the ironing of a shirt, that is, the back part thereof, when said bottom part 55

12 is brought up against the center part in an upward movement of the former.

The bottom part 12 is slidable in its up and downward motion, upon two telescopic members 5 25 and 26, of a cylindrical shape, of which members, one 26 is secured to the bottom part 12, while the other member 25 is secured to a frame work 27.

Said bottom part 12 is upon each side thereof 10 provided with an upwardly extending and slightly outwardly slanting arm 28, adapted to act upon and accommodate the sleeve 53 of a shirt during the ironing operation.

The top part 10 is secured to the arms 29 and 15 30 of a bifurcated member 31, as shown in Figure 3, which member in turn is hingedly attached, as shown at 33 in Figure 1, to a standard 32, forming part of the frame work 27, upon which the device rests. Preferably the top part 10 is 20 provided with an operating handle or the like 65 and a spring 66 which tends normally to raise the top part 10 about pivot 33. It will be understood that, in accordance with conventional practice, a suitable weight might replace the spring 66.

25 The top part 10 is formed with a lower surface of a somewhat curved shape, as shown at 34 in Figure 1, adapted to register with the upper surface of the center part 11, when the part 10 is lowered upon the latter in an ironing operation.

30 A member 35 slidable in a longitudinal direction, is arranged upon each side of the top member 10; said slidable member is bent upon itself to form double walls with a groove 36 between said walls 38 and 39, as may be seen in 35 Figure 4. In the groove between these walls is mounted a member 37 carried on arm 37a, as may be seen in Figure 1, which member has its top portion somewhat curved and shaped to accommodate the cuffs 42, as shown in Figure 3, 40 of a shirt during the ironing operation. Between the said walls 38 and 39 is further pivotally mounted a member 40, pivoted as by pin 40a, which terminates in a somewhat cup-shaped end portion 41, adapted, also, to accommodate the 45 cuffs in said ironing operation of a shirt, as said cup-shaped member 41 during the aforesaid operation is made to close upon and embrace the cuffs 42 arranged upon the top of the member 37. A clear idea of this latter operation, 50 consummated, may be obtained from Figure 3.

The sliding member 35 is, as shown in Figure 1, formed with a forwardly projecting end portion 43, which in turn is made with a downwardly and inwardly slanting surface 44. In this connection, it will be noted that the bottom part 12 is, also, formed with a forwardly projecting portion 45, as shown in Figure 1, so that when in closing and lowering the top part 10 upon the center part 11, the projecting portion 45 of the 55 bottom part 12 will automatically cause the member 35 to slide backward as the slanting surface 44 upon the extended portion 43 is acted upon by the slanting surface 46 of the stationary part 45 of the bottom part 12.

60 The top part 10 has two prongs 47 and 47', upon which a semi-circular member 48 is mounted and adapted to secure a member 49 in position; said member 49 has the form of a ring and is slightly cone-shaped and adapted to embrace the collar of a shirt during ironing operation, as said collar is arranged upon the member 16. Said ring member 49 terminates in the extended end portions 50 and 50'; these end portions are made to be acted upon, and, in turn, press the ring 70 member 49 around the collar 54, when during

the operation the member 35, as hereinbefore stated, slides back, whereby the upper slanting flanges 51 and 51' of said member 35 will tend to close, or bring nearer to each other the said end portions 50 and 50'. 5

It is obvious that changes may be made in the form, construction and arrangement of the several parts, as shown, within the scope of the appended claims, without departing from the spirit of the invention, and I do not, therefore, 10 wish to limit myself to the construction and arrangement shown and described herein.

What I claim as new, and desire to secure by Letters Patent of the United States, is:—

1. A laundry ironing and pressing machine, 15 comprising a center part, adapted to have a shirt mounted thereon, said center part being made with a tubular opening therethrough and having one end thereof made with a reduced portion in its upper surface, a standard forming part of a 20 frame-work, and a hollow shank connecting said center part to the standard, a vertically movable cone-shaped member arranged in the reduced portion at one end of the center part and adapted to have the collar of a shirt mounted thereon, 25 means arranged through the hollow shank and tubular opening in the center part, whereby to actuate the cone-shaped member; a top part capable of descending upon and closing over the center part, said top part having means mov- 30 ably attached upon each side thereof, said means comprising a member formed with double walls and having the outer side of the outer wall thereof slightly rounded, a bottom part, a side piece integrally formed upon each side of the latter, said side piece being curved to correspond with the aforesaid outer wall, the bottom part being adapted to cooperate with the center part, and the side pieces of said bottom part being made to cooperate with the aforesaid outer walls of the means attached to the movable top part, when the latter is lowered upon the center part, substantially as shown and described.

2. In a device, as claimed in claim 1, and wherein telescoping members are provided, which are adapted to accommodate the bottom part in its vertical movement.

3. In a device, as claimed in claim 1, and wherein telescoping members are provided, which are adapted to accommodate the bottom part in its vertical movement, one of said telescoping members being integrally secured to the bottom part, and a frame work having the other telescoping member integrally attached thereto, substantially as shown and described.

4. A laundry ironing and pressing machine, 60 comprising a center part adapted to have the body portion of a shirt mounted thereon, a cone-shaped member disposed at one end of said center part and adapted to have the collar of a shirt arranged thereon; a bottom part made to cooperate with said center part, and a top part adapted to be lowered upon the latter, a member arranged upon each side of the top part, said member being formed with double walls and made with a groove between the latter and adapted to perform a limited sliding movement upon said top part, and means secured to said member, whereby to accommodate the cuffs of a shirt during the ironing of the said cuffs. 70

5. A laundry ironing and pressing machine, comprising a center part adapted to have the body portion of a shirt mounted thereon, a cone-shaped member disposed at one end of said center part and adapted to have the collar of a

shirt arranged thereon; a bottom part made to cooperate with said center part, and a top part adapted to be lowered upon the latter, a substantially ring-shaped member arranged at one end of said top part, said ring member being formed with legs adapted to project slightly over and above the top part, a sliding member arranged upon each side of the top part, said sliding member being formed with a slanting side portion, whereby to engage a leg of said ring member during operation, said sliding member being made to form double walls and having a groove between the latter, and means arranged upon said sliding member, whereby to accommodate the cuff of a shirt during the ironing thereof.

6. In a device, as claimed in claim 5, and including means arranged in said groove comprising an arm terminating in a member formed with a curved top portion, adapted to receive a cuff thereon, a cup-shaped member adapted to close upon the cuff disposed on said curved portion, and an arm integral with the cup-shaped member and pivotally secured in said groove of the sliding member.

7. A laundry ironing and pressing machine, comprising a center part adapted to have the body portion of a shirt mounted thereon, a cone-shaped member disposed at one end of said center part and adapted to have the collar of a shirt arranged thereon; a bottom part adapted to close upon the center part, and a top part adapted to be lowered upon the latter, a cone-shaped ring member adapted to embrace the collar upon the cone-shaped member at the end of the center part, a member slidably arranged upon each side of the top part, said member being formed with double walls, an arm disposed between said double walls and being formed with an enlarged portion adapted to accommodate a cuff thereon, and a cup-shaped member pivotally mounted upon said slideable member and made to close upon said enlarged portion during operation.

8. A laundry ironing and pressing machine comprising a center part made to receive the bosom of a shirt thereon, a vertically movable cone-shaped member arranged at one end of said center part and adapted to have the collar of a shirt mounted thereon; a top part adapted for cooperation with the center part, means arranged upon each side of said top part and adapted to have the cuffs of a shirt placed thereon, and a cup-shaped member pivotally connected to the top part upon each side thereof and adapted to engage the cuffs arranged upon the aforesaid means, a substantially ring-shaped member arranged at one end of said top part and adapted to embrace the cone-shaped member with the collar mounted upon the latter; a bottom part, side walls integral with the latter and extending in an upward direction, said walls being adapted to have a sleeve mounted between the latter and the top part, in the shirt ironing operation, substantially as shown and described.

9. A laundry ironing and pressing machine comprising a center part made to receive the bosom of a shirt thereon, a vertically movable cone-shaped member arranged at one end of said center part and adapted to have the collar of a shirt mounted thereon, and means for actuating said cone-shaped member; a top part adapted for cooperation with the center part, a sliding member arranged upon each side of said top part, and a curved member attached to the latter and adapted to have the cuff of a

shirt mounted thereon, a cup-shaped member pivotally secured to each side of said sliding member and adapted to substantially embrace the curved member with the cuff arranged upon the latter, a ring-shaped member adapted to embrace said cone-shaped member with the collar mounted upon the latter, said ring-shaped member having arms integral therewith and extending above the upper surface of the top part proper, said arms being actuated by said sliding members; a bottom part, upwardly extending walls integrally formed upon each side of the latter and adapted to have the sleeves of a shirt arranged between themselves and said sliding members, during an ironing operation.

10. In a device, as claimed in claim 9, and wherein the sliding members are made with forwardly projecting end portions, said end portions being formed with downwardly and inwardly slanting surfaces, and the bottom part being made with a forwardly projecting slanting portion adapted to engage and actuate the end portions of the sliding members during operation.

11. A laundry ironing and pressing machine comprising a center part adapted to receive and support the body portion of a shirt, an upwardly extending member arranged to receive the collar of said shirt, a top part adjustably mounted and adapted to be brought into and out of cooperative engagement with said center part, a sliding formation arranged upon each side of said top part, a cuff-supporting member at each side of the machine and adapted to have the cuff of said shirt mounted thereon, a cuff-pressing member adapted substantially to overlie each cuff-supporting member to press a cuff supported upon the latter, a bottom part having upwardly extending portions formed at each side thereof adapted to overlie the sleeves of said shirt arranged adjacent said sliding portions, means for adjustably positioning said bottom part into and out of operative engagement with said center part, means for causing displacement of said sliding formations responsive to the bringing together of said bottom, top and center parts, means adapted to externally engage the supported collar of said shirt, and means responsive to the displacement of said sliding formations for bringing said last mentioned means into firm contact with said collar of said shirt to be ironed.

12. A laundry ironing and pressing machine comprising a center part formed to receive the bosom of a shirt thereon, an adjustably mounted cone-shaped member arranged at one end of said center part and adapted to have the collar of a shirt mounted thereon, and means for actuating said cone-shaped member, a top part adapted for cooperation with the center part, a sliding member arranged upon each side of said top part, a cuff-supporting member at each side of the machine adapted to have the cuff of a shirt mounted thereon, a cuff pressing member pivotally arranged at each side of said machine and adapted respectively to substantially overlie the cuff-supporting members with the cuffs arranged upon the latter, a ring-shaped member adapted to embrace said cone-shaped member with the collar mounted upon the latter, said ring-shaped member having arms extending therefrom above the upper surface of the top part proper, said arms being actuated by said sliding members, a bottom part, upwardly extending walls integrally formed upon each side of the latter and adapted to have the sleeves of a shirt arranged between themselves and said

sliding members, during an ironing operation, and means for moving said bottom part in an upward and downward direction.

13. A laundry ironing and pressing machine comprising a center part made to receive the bosom of a shirt thereon, a vertically movable collar-supporting member arranged at one end of said center part and adapted to have the collar of a shirt mounted thereon, a top part adapted for cooperation with the center part, means arranged upon each side of said machine and adapted to support the cuffs of said shirt placed thereon, and a cuff-pressing member pivotally connected to the top part upon each side thereof and adapted to engage the cuffs supported upon the aforesaid means, a member adapted to engage the cuffs arranged upon the aforesaid means, a member adapted to embrace the collar-supporting member with the collar mounted upon the latter, and a bottom part having side walls extending in an upward direction, said side walls being adapted to have a sleeve mounted between the latter and the top part, in a shirt ironing operation.

14. A laundry ironing and pressing machine comprising a center part made to receive the

bosom of a shirt thereon, a collar-supporting member arranged at one end of said center part and adapted to have the collar of a shirt mounted thereon, a top part adapted for cooperation with the center part, means arranged upon each side of said machine and adapted to support the cuffs of said shirt placed thereon, and a cuff-pressing member pivotally connected to the top part upon each side thereof and adapted to engage the cuffs supported upon the aforesaid means, a member adapted to embrace the collar-supporting member with the collar mounted upon the latter, a bottom part having side walls extending in an upward direction, said side walls being adapted to have a sleeve mounted between the latter and the top part in a shirt ironing operation, said bottom part and said top part being arranged to move in an upward and downward direction, and means responsive to the bringing together of said top, center and bottom parts for tightening said member embracing the collar supporting member about the latter.

AUGUST DAHLER.
